UNITED STATES PATENT OFFICE.

CONANT W. RUTH, OF WAKEFIELD, MASSACHUSETTS.

RAILWAY-TIE PLATE.

1,316,649.

Specification of Letters Patent. Patented Sept. 23, 1919.

Application filed June 2, 1916, Serial No. 101,371. Renewed February 26, 1919. Serial No. 279,414.

To all whom it may concern:

Be it known that I, CONANT W. RUTH, a citizen of the United States, residing at Wakefield, in the county of Middlesex and State of Massachusetts, have invented certain Improvements in Railway-Tie Plates, of which the following description, in connection with the accompanying drawings, is a specification, like reference characters on the drawings indicating like parts in the several figures.

It is now comparatively common in railway construction to use a tie plate of some description between the rails and the ties that support them. These plates are designed to accomplish one or more of the following objects: first, to prevent the rails from cutting into the ties, second, to prevent the rails from creeping longitudinally on grades; and third, to support the rails against the forces tending to spread them apart or to tip over the outer rails on curves. While a great variety of devices of this general character have been proposed heretofore, only a very few of these constructions have attained any substantial degree of commercial success and these have not proved entirely satisfactory, due usually either to the fact that they cannot be relied upon to perform the functions for which they were intended, or else that they are so expensive, either in first cost or in the cost of the labor required in using them, that they can only be used in places where some device of this character is absolutely necessary.

The present invention has for its chief object to devise a tie plate which can be economically manufactured and easily installed and will satisfy the practical requirements of devices of this character. The invention will be readily understood from the following description, reference being made to the accompanying drawings, in which—

Figure 1 is a perspective view of a tie plate embodying the invention in the form now preferred by me, and

Fig. 2 is a vertical, cross sectional view taken substantially on the line 2—2, Fig. 1, and illustrating the manner in which the plate is used.

The construction shown in the drawings comprises a main plate 2, which may be made out of any suitable material such, for instance, as malleable iron or steel. An aperture 4 is formed through this plate and two rail holding lugs 6 are formed on it.

These lugs may be punched or struck up from the plate 2, and the aperture 4 may be formed in the same operation by punching out a piece of material of the required dimensions. A notch 8 may also be formed on one end of the plate 2 to receive a spike 9 (see Fig. 2). A smaller plate 10 fits loosely in the slot or aperture 4 formed in the main plate 2 and is provided with an upturned lip 12, which is shaped to fit over one edge of the base of the rail 14, as clearly shown in Fig. 2. If the aperture 4 is formed by punching material out of the plate 2, as above described, the part of the plate so punched out, and which otherwise would be scrapped, may be utilized to make the plate 10. In any event this plate should be of substantially the same thickness as the main plate 2 so that it will fill the slot 4 vertically when in its normal or operative position.

In using this device, the plate 2 is positioned under the rail 14 and the clamping plate 10 is inserted in the slot 4. The spike 9 is driven into the tie 16 and this tie is then drilled to receive two lag screws, one of which is shown in Fig. 2 at 18. Each of these lag screws is provided with a squared head 19 and a tapered portion 20 between this head and the shank of the screw. As these screws are turned down tightly, the tapered parts 20 crowd into the space between the outer edge of the lip 12 and the outer wall of the aperture 4 and force the lip of the plate 10 into its rail clamping position, as shown in Fig. 2. The opposite edge of the base of the rail, of course, has previously been positioned under the ends of the lugs 6, which limit the sliding movement of the rail over the plate in this direction; and consequently, when the lag screws 18 are turned down securely they serve not only their ordinary functions of fastening the rail, and incidentally the tie plate, to the tie 16, but they also clamp the base of the rail securely between the parts 12 and 6. Any substantial slipping or creeping of the rail on a grade thus is prevented. Preferably the outer wall of the aperture 4 is notched or slightly scalloped, as indicated at 22, to afford a better seat for the conical parts 20 of the two lag screws 18. This wall of the aperture 4 backs up the lag screws and facilitates their crowding action on the clamping plate 10 as above described.

It is obvious that this tie plate can be economically manufactured and that its use

requires an amount of additional labor so small as to be immaterial. The lag screws used are similar to those much used in railway construction. Preferably the lag screws 5 18 are placed on the "inside" of the rail, that is, between the two rails, so that any tendency of the rail 14 to spread away from its companion rail is resisted by both the lag screws 18 and by the spike 9. It will also 10 be evident that any tendency of the rail to tip over will be effectually resisted by the two lag screws 18, both of which would have to be pulled partially out of the tie before the rail could be tipped appreciably.

15 Having thus described my invention, what I claim as new and desire to secure by Letters Patent of the United States is:

1. A railway tie plate, having one or more rail holding lugs formed integral therewith, 20 and having an aperture formed therethrough toward which said lugs point, a rail clamping member arranged to fit loosely in said aperture, but of such dimensions as to leave a space for the passage of a rail fastening 25 device between said member and the outer wall of said aperture.

2. A device of the character described comprising a flat plate having an aperture formed therethrough, one or more rail holding lugs integral with said plate and extending 30 toward said aperture, and another plate shaped to fit loosely in said aperture and having a rail holding lip formed along its edge opposite said lugs and extending toward 35 said lugs, said plates being of substantially the same thickness.

3. The combination of a railway tie, a plate supported on said tie, a rail resting on 40 said plate, a device overlying one edge of the base of said rail to limit the movement of the rail toward one end of the plate, said plate having an aperture formed there-

through near its opposite end, and means for crowding the base of said rail against said device, said means comprising a member 45 threaded into said tie and extending through said aperture between said rail and the outer wall of said aperture, and having a tapered head arranged to bear against said wall. 50

4. The combination with a tie, of a tie plate resting on said tie and having an aperture formed therethrough, a rail supported on said plate, a rail clamping plate of substantially the same thickness as said tie plate 55 constructed to fit in said aperture under said rail and having an upturned lip overlying one edge of the base of the rail, one or more lugs integral with said tie plate and overlying the opposite edge of the base of said rail, 60 and one or more lag screws extending through said aperture into the tie and coöperating with the wall of said aperture to crowd said clamping plate into its rail clamping position. 65

5. The combination of a railway tie, a plate supported on said tie and having an aperture formed therethrough, a rail resting on 70 said plate, means near one end of said plate constructed to overlie one edge of the base of said rail, a smaller plate positioned in said aperture under the rail and having a rail clamping lip overlying the opposite edge of the base of said rail, and rail fastening means extending through said aperture 75 into said tie and constructed and shaped to bear against the outer edge of said clamping plate and the outer wall of said aperture, and to crowd said lip into clamping engagement with the base of said rail. 80

In testimony whereof I have signed my name to this specification.

CONANT W. RUTH.
